UNITED STATES PATENT OFFICE.

JOHN RUNEY, OF SOMERVILLE, MASSACHUSETTS.

DESIGN FOR A HANGING-VASE.

Specification forming part of Design No. 5,406, dated December 5, 1871.

To all whom it may concern:

Be it known that I, JOHN RUNEY, of Somerville, in the county of Middlesex and State of Massachusetts, have invented a new and original Design for Ornamenting Hanging-Vases; and do hereby declare the same to be fully described in the following specification, reference being had to the accompanying drawing forming a part thereof, the said drawing representing a side view of a vase, as ornamented with my said design.

My invention relates simply to the ornamentation of a hanging-vase or flower-pot, without reference to the shape of the same.

In the said drawing, A represents a vase of ordinary form and construction; a denotes the ornamentation, which consists of two flowers with

their leaves and stems intertwined. These flowers are representations of roses, and may be either white, red, yellow, or other desirable color. These may be formed thereon or applied thereto, in any known way. The best and readiest method is to first draw or paint the design upon paper, and color the same, and then transfer it to the sides of the vase by a well-known process.

Having described my invention, what I claim is—

The design for ornamenting a hanging-vase as described and shown.

JOHN RUNEY.
